SUPPORT FOR GARMENT HANGERS

Donald F. Furlong, Jackson, Mich.

Application March 21, 1955, Serial No. 35,117

Term of patent 14 years

(Cl. D80—8)

F-2 - 1

F-2 - 2

Fig. 1 is a front elevational view of a support for garment hangers showing my design.

Fig. 2 is a side elevational view, and

Fig. 3 is a front perspective view thereof.

I claim:

The ornamental design for a support for garment hangers, as shown.
